Fig. 5.

Fig. 6.

Fig. 7.

Fig. 8.

FIGURE 1 is a front perspective view of a gasoline pump showing one embodiment of our new design, the rear, not shown, being substantially like the front shown;

The undisclosed side of the gasoline pump is substantially the same in appearance as the side shown in each embodiment.

This application is a continuation of our earlier filed copending applications, Serial Numbers D. 68,795 and D. 68,796, filed February 13, 1962, and now abandoned, and is a division of our earlier filed copending application Serial Number D. 68,797, filed February 13, 1962.

We claim:

The ornamental design for a gasoline pump or similar article, as shown and described.
